ATTORNEY.

UNITED STATES PATENT OFFICE

HEINRICH ROMBERG, OF DUSSELDORF, GERMANY, ASSIGNOR TO RHEINISCHE-METALLWAAREN- UND MASCHINENFABRIK, OF DUSSELDORF-DERENDRF, GERMANY, A CORPORATION OF GERMANY

SPRING MOUNTING OF FIELD GUNS

Application filed March 18, 1930, Serial No. 436,769, and in Germany February 14, 1929.

In known spring mountings for guns in which the springs can be hydraulically locked, the carriage is carried by metal springs disposed in a casing filled with liquid, mounted on the carriage axle; the springs abut at one end against a support provided in the casing, and at the other end against pistons displaceable fluid-tight in the casing; the piston rods projecting from the casing engage with supporting members inserted between the axle and carriage (as shown, for example, in the German Patent No. 466,335). The pistons divide the interior of the casing into three compartments filled with liquid, but which are in communication by means of channels for the passage of the liquid, valves or other closing devices being provided in the passages. When the passages are open, the springs are allowed free play, but when the passages are closed the springs are locked.

The metal springs of these devices are liable to be broken and, since they are entirely surrounded with the casing filled with liquid, are not easily exchanged.

According to the invention, these drawbacks are obviated by replacing the metal springs by an air spring.

The cylinders in which the pistons slide are entirely filled with liquid and the air acting as the springs is enclosed in separate chambers partly filled with liquid. Each of these chambers is connected by a passage for the flow of liquid, and which can be closed at will, with a compartment of the cylinder on one or other side of the pistons. When the passages are open, the spring system has free play; when the passages are closed it is locked.

While, therefore, in the known spring mountings for guns in which the springs can be hydraulically locked, the compartments of the cylinder on each side of the pistons are connected together by passages for the flow of liquid which can be closed; in the arrangement according to the invention each of the three compartments of the cylinder is connected by a passage with a chamber, partly filled with liquid and partly with air, so that either all three passages,

or at least the passages leading from the pressure compartments of the cylinder, can be closed.

An example of an embodiment of the device according to the invention is represented in the accompanying drawing.

Figure 1 is a vertical section through an axle showing the general arrangement of the mounting.

Figure 2 is a similar section on a larger scale of the hydraulic spring and air containers.

The carriage *a* rests on the horizontal arms of the angular levers *c* applied to the axle *b*. To the vertical arms of the angular levers are linked the piston rods *d* of pistons *e*, which are easily displaceable but fit tightly in the cylinder *f* which is filled with liquid. The interior of the cylinder *f* is divided by the pistons into three liquid-tight compartments *f*₁, *f*₂, *f*₃. The compartments *f*₁ and *f*₂ are referred to in the following description as pressure compartments, the compartment *f*₃ as a damping compartment. At the upper part of the three compartments there is a passage *g*₁, *g*₂, *g*₃ for liquid and each of them is connected to the bottom of a container *h*₁, *h*₂, *h*₃ partly filled with liquid.

Each container is completely closed and contains air above the liquid level. While, however, the container *h*₃, afterwards called the damping air container, connected to the damping compartment, contains air above the level of the liquid of about atmospheric pressure, the other containers *h*₁ and *h*₂ (in the following called the air pressure containers) are filled with air compressed by the pistons *e* loaded with the weight of the carriage. Closing devices *i*₁, *i*₂, are provided in the passages *g*₁ and *g*₂ which connect the pressure compartments *f*₁, *f*₂ of the cylinder *f* with the containers *h*₁, *h*₂.

In order to lock the spring system the passages *h*₁ and *h*₂ are closed by rotating the closing devices through 90 degrees. When the passages *h*₁ and *h*₂ are closed, the liquid contained in the pressure compartments of the cylinder *f* cannot be pressed by the pistons *e* into the air containers, and the liquid in the air containers cannot be forced as the air expands again into the cylinder; conse-

quently, as the air cannot be compressed and the liquid in the pressure chambers is incompressible, the pistons *e* are held in the position they have at any time.

On the sudden release of the spring system, it might happen that the pistons *e* were impelled against one another. This is avoided by the liquid filling the damping compartment *f₃* being forced out of the compartment when the pistons approach one another and the air contained in the container *h₃* compressed, the increased pressure set up opposing the movement. Also, frictional damping occurs, in the first place by the friction of the liquid flowing in the passages *g₁*, *g₂*, *g₃*, and secondly by the braking action set up in the compartment *f₃*. In one piston there is provided a plunger *k*, which, when the spring system is suddenly relieved, is inserted in the cylindrical recess *l* of the other piston, so that pressure is exerted on the liquid contained in the cylindrical recess.

The liquid is forced at high velocity through narrow longitudinal grooves in the plunger. The great resistance to flow obtained in this way effectively prevents impulsive movements of the pistons.

I claim:

1. A spring mounting for the carriage of a field gun, comprising a cylinder, a pair of pistons axially displaceable, fluid-tight in the cylinder, a pressure compartment, completely filled with liquid, in the cylinder on the outward side of each piston, closed receptacles partly filled with liquid containing air under pressure, passages connecting said receptacles with said pressure compartments, a device inserted in each of said passages adapted to close at will said passages, a damping compartment in the cylinder between said pistons, a damping receptacle partly filled with liquid, containing air substantially at atmospheric pressure, and a passage connecting said damping receptacle with said damping compartment.

2. A spring mounting for the carriage of a field gun according to claim 1, comprising also a plunger rod secured to one piston on the side towards the centre of the cylinder and adapted, when the pistons approach closely, to enter a corresponding cylindrical recess on the side of the other piston.

3. A spring mounting for the carriage of a field gun according to claim 1, comprising also a plunger rod secured to one piston on the side towards the centre of the cylinder and adapted, when the pistons approach closely, to enter a corresponding cylindrical recess on the side of the other piston, and longitudinal grooves in said plunger rod allowing a restricted flow of the liquid from the recess as the plunger rod enters it.

In testimony whereof I have affixed my signature.
